ATTORNEY

UNITED STATES PATENT OFFICE.

OSCAR KRAUSE, OF FAR ROCKAWAY, NEW YORK.

DESIGN FOR A TEXTILE FABRIC.

Application filed December 22, 1925. Serial No. 15,824. Term of patent 3½ years.

To all whom it may concern:

Be it known that I, OSCAR KRAUSE, a citizen of the United States, residing at Far Rockaway, in the county of Queens, State of New York, have invented a new, ornamental, and original Design for a Textile Fabric, of which the following is a specification, reference being had to the accompanying drawing, forming a part thereof.

The figure is a face view of a textile fabric, showing my new design.

I claim,

The ornamental design for a textile fabric, substantially as shown.

OSCAR KRAUSE.
